MACHINE FOR APPLYING MARGINAL COATINGS TO ARTICLES

Herbert R. Polleys, New Haven, Conn., assignor to
 United States Rubber Company, New York,
 N. Y., a corporation of New Jersey

Application July 27, 1940, Serial No. 347,909

6 Claims. (Cl. 12—80)

This invention relates to a machine for applying a liquid coating to the lower margin of an article. The invention relates particularly to a machine for applying an adhesive coating of latex to the lower margin of a shoe by which the foxing strip is adhered to the shoe.

Heretofore marginal coatings have been applied to articles by brushing it on. The brushes do not apply a sufficiently heavy coating for some purposes and where the coating material is gummy, as in the case of a latex adhesive, the brushes, as well as other parts of the machine coming in contact with the coating must be cleaned from time to time whenever the operation of the machine is stopped for an appreciable length of time. These cleaning operations require considerable time, particularly when the parts of the machine coming in contact with the coating liquid are inaccessible.

In accordance with the present invention the coating liquid is flowed upon the margin of the article to be coated, and in this way the heavier coating is applied, and the operation of cleaning the brushes formerly used is eliminated. Where the machine is used for applying an adhesive coating of latex to the lower margin a shoe for adhering the foxing strip thereto, an excess quantity of latex is flowed on the margin and it runs off onto a support where it is transferred to the bottom of the shoe for adhering the sole thereto. In order that the machine may be easily cleaned some of the parts are either movable out of their operating position or removable so that they can be cleaned and other parts are made accessible for cleaning.

Other advantages and important features of the invention will be more clearly understood by referring to the following description and the accompanying drawings, in which:

Fig. 1 is a side elevational view of a machine embodying the invention, and showing the machine in its operating position with some of the parts broken away for the purpose of disclosing the interior mechanism;

Fig. 2 is a plan view of the machine with parts broken away;

Fig. 3 is an elevational view of the machine showing it in its non-operating position with parts moved to positions for cleaning and for replenishing the coating liquid supply;

Fig. 4 is a detail plan view of the station where the coating liquid is flowed upon the article;

Fig. 5 is a cross-sectional view of the liquid coating supply and applying mechanisms taken on line 5—5 of Fig. 4;

Fig. 6 is a cross-sectional view of the liquid coating supply and applying mechanisms taken on line 6—6 of Fig. 2;

Fig. 7 is a side elevational view of the liquid coating applying mechanism showing the operation of applying a marginal coating to the lower edge, or fixing margin of a shoe in which the coating is being applied to the side of the shoe; and

10 Fig. 8 is a side elevational view of the liquid coating applying mechanism showing the operation of applying a marginal coating to the lower edge, or foxing margin of a shoe in which the coating is being applied to the heel portion.

This invention is illustrated in reference to a machine for applying an adhesive coating of latex to the bottom edges of shoes for the purpose of adhering a rubber foxing strip to the shoe, along the coated margin. In this operation it is im-

15 portant to apply a relatively thick coating to the shoe so that the width of the coated margin will be substantially uniform and the top edge will be sharp and well defined to give the shoe a neat appearance.

20 Referring particularly to Figs. 5, 6, 7 and 8, a liquid latex adhesive coating material 10 is conveyed from a tank 11 by a rotating drum 12 to a downwardly inclined trough 13 which discharges the latex from its discharge end 14 upon the

25 margin 15 of the shoe 16 to which the foxing strip is to be applied. The shoe 16 is supported by a plate 17 having a relatively small projection 18 adjacent to the discharge orifice 14 and an elevated portion 19 which is adapted to support the toe and ball portion 20 of the bottom of the shoe in certain positions as the lower edge of the shoe is turned around on the projection 18 in front of the discharge end 14 as the coating is flowed upon its margin. A rotatable disc

30 21 having an extended lip 22 is positioned above the trough 13 and travels along the upper edge of the marginal coating 15 in a clockwise direction as indicated by the arrow so as to control the upward splash of the coating fluid and produce a well defined, smooth upper edge 23 on the marginal coating 15.

In order that the width of the marginal coating 15 may be made substantially uniform in the case of an article, such as a shoe having a curved base as at the shank 24, the projection 18 adjacent to the end 14 of the trough is made relatively small so that it will fit the curve of the shank 24 as this portion of the shoe is rotated over the support 18 to apply the marginal coating 15 above that bottom area. The elevated

portion 19 is employed to steady the toe or ball portion 20 of the shoe while the marginal coating 15 is applied along the heel area of the shoe and thereby act as a guide and as an aid in maintaining the uniformity of the width of the coating.

It will be understood that an excess amount of coating liquid is flowed upon the margin 15 in order to insure the relatively thick or heavy coating. Some of the excess liquid flows back into the supply tank 11 through an opening 25 in the supporting plate 17 and down a spout 26 into the tank. Other portions of the excess coating liquid flows down the supporting plate 17 and from the margin 15 of the shoe upon the elevated portion 19 and coats the bottom portion of the shoe for the purpose of adhering the sole thereto. As shown in Figs. 1 and 2, the excess coating liquid may flow from the bottom edge 27 of the elevated portion 19 of the supporting plate 17 into a catch tank 28. In order to remove any excess coating liquid from the bottom of the shoe 16 the bottom is wiped across the top of a rubber wiper 29 which is secured by a wing nut 30 to the side of the supporting plate 17. The wiped off coating liquid flows down the wiper into the tank 28.

Referring to Figs. 1 and 2, the rotatable disc 21 and the rotatable drum 12 are driven by a motor 31 on the machine frame F which in turn is supported by a pedestal P resting on a base, not shown. The drum 12 is driven by a pulley 32 on the motor shaft 33. A belt 34 is driven by the pulley 32 and drives a pulley 35 keyed to a shaft 36 journaled in a gear case 37 secured to the frame F. A gear 38 is keyed to the shaft 36 and drives a larger gear 39 which is keyed to an idler shaft 40 having a gear 41 keyed thereto and driving a gear 42 which is keyed to a shaft 43 to which the drum 12 is keyed.

The rotatable disc 21 is driven from a pulley 44 on the motor shaft 33. A belt 45 is driven by the pulley 44 and drives a pulley 46 (Fig. 1) which is keyed to a shaft (not shown) mounted in a gear case 47. The gear case 47 contains reduction gears which are driven from the pulley 46 and drive the meshing beveled gears 48, one of which is keyed to the shaft 49 to which the rotatable disc 21 is secured. A scraper 50 (Figs. 3 and 4) is mounted on the gear case 47 and its lower end contacts rotatable disc 21, as more particularly shown in Fig. 4, to keep the upper surface of the disc from collecting batches of coating liquid material thereon, particularly in the case where latex is used, which tends to coagulate on the surface.

For the purpose of moving the rotatable disc 21 away from the trough 13 and the coating liquid transfer drum 12 so that the trough may be removed and the drum may be made accessible for cleaning, the gear casing 47 which carries the disc 21 is mounted upon a base 50' which is pivoted on a pin 51 mounted in the side frames 52 of the machine. As shown in Fig. 3, the disc 21 has been pivoted upwardly about the pin 51 to the cleaning position. The base is locked into its lower operative position, as shown in Fig. 1, by a hook 53 which extends underneath a cross pin 54 in the side frame 52. The hook 53 forms one end of and is operated by a lever 55 which is pivotally mounted on a pin 56. The base 50' is provided with an arm 57 which is adapted to strike against a spring abutment 58 to cushion the downward movement of the base 50' and the mechanism carried thereby. The abutment 58

is mounted in one of the side frames 52 and the spring tension on the abutment may be adjusted by the nuts 59 on the threaded stem 60.

Referring to Fig. 5 the bottom of the trough 13 is cut out so as to permit a portion of the upper periphery of the drum 12 to extend into the opening. The edge 61 of the opening in the trough is resiliently held against the periphery of the drum 12 by a spring pressed arm 62 which cooperates with the upper end of the trough and tends to pivot it about the pin 54 which fits into notches 63 in the sides of the trough. Referring to Fig. 3, the arm 62 is mounted on a shaft 64 oscillatably mounted in the side frames 52. An arm 65 is keyed to the shaft 64 on the outside of the side frames 52 and is pulled downwardly by a tension spring 66 having one end secured to the arm 65 and the other to the frame of the machine. The pressure with which the lower edge 61 of the trough is held against the periphery of the drum 12 is controlled by an adjustable set screw 67 mounted in the side frame 52 and having an end cooperating with the outer end of the arm 65. When the rotatable disc 21 has been pivoted upwardly to the position shown in Fig. 3, the trough 13 may be removed from the machine by manually lifting the arm 65, which lowers the arm 62 and permits the notches 63 in the trough 13 to be disengaged from the pin 54. The trough 13 may then be pulled lengthwise to the left as viewed in Fig. 3, and removed from the front of the machine.

The coating liquid is supplied to the supply tank 11 from a reservoir 68, and the feed therefrom is so arranged that the liquid level in the supply tank 11 is maintained at a substantially constant height. The reservoir 68 is made in the form of a bottle, which is pivotally supported by a rod 69 having its lower end pivotally mounted on a pin 70 in the frame F. The reservoir 68 is secured to the rod 69 by an upper socket 71 and a lower semi-circular support 72. The bottom of the bottle 68 fits into the socket 71, and it is supported on the shoulder adjacent to the neck by the support 72. The socket 71 and the support 72 are secured to the rod 69. The socket 71 is secured with a clamp 73 which is split and fits around the top of the rod 69. A screw 74 is threaded into the end of the rod 69 and its head extends over and prevents the clamp from slipping off the rod. The clamp 73 may be tightened around the rod 69 by a hand wheel 75 mounted on a pin 76 extending through one side of the clamp and having its end threaded into the other side of the clamp and adapted to draw the sides together around the rod. A cap 77 is screwed onto the mouth of the bottle 68, or otherwise secured thereto, and it is provided with an outlet nozzle 78 which is adapted to discharge the coating liquid into an open canal 79 which leads into the supply tank 11 shown in Fig. 2. When the liquid level of the coating liquid, which is always the same in the tank 11 and the canal 79, falls below the end of the nozzle 78, the coating liquid flows from the bottle into the supply tank 11 until the liquid level rises above the end of the nozzle. The flow from the bottle 68 is then stopped and in this manner the liquid level is maintained substantially constant.

In order to refill the bottle 68, it is pivoted about the pin 70 from the position shown in Fig. 1 to that shown in Fig. 3. The bottle 68 being in its upright position, the cap 77 may be removed and the bottle may be filled. In order to bring the bottle back to the position shown

in Fig. 1, the operator places his finger over the end of the nozzle 78 and then pivots the bottle to its inverted upright position. The operator's finger is then removed and the flow of coating liquid to the canal 79 and tank 11 is continued as previously described.

The canal 79 is fixed to the supply tank 11. The tank 11 is supported by a vertically movable support 80, and the projecting end of the canal 79 is supported by a bracket 81 secured to the frame of the machine. Referring to Fig. 6, the support 80 is held in its operative position by an arm 82 which is pivoted on the support by a pin 83. The arm 82 in turn is supported by a projection 84 on the frame. The support 80 is provided with a downwardly extending hollow projection 85 which telescopes over an upwardly extending hollow projection 86 attached to the frame. A rod 87 having an operating knob 88 thereon extends through the hollow projection 86 and is threaded into the bottom of the downwardly extending projection 85. The outer projection 85 prevents the gumming up the slide rod 87 by any overflow of the coating liquid. The supply tank 11 and the canal 79 may be removed from the machine by manually grasping the knob 88 and moving the arm 82 to the dotted line position as shown in Fig. 6. After the tank has been lowered below the periphery of the drum 12 it and the canal 79 may be removed from the machine.

As more clearly shown in Figs. 2 and 5 a scraper 89 is adapted to cooperate with the periphery of the coating transfer drum 12 so as to control the quantity of coating liquid transferred by the drum to the trough 13. The scraper 89 is mounted on a square bar 90 which slidably fits into a similarly shaped guideway 90 formed in the frame. The scraper 89 may be adjusted toward or away from the periphery of the drum 12 by a hand wheel 92 which is screw-threaded on a projection 93 extending from the end of the bar 90. The hand wheel 92 is fixed against axial movement and is rotatably mounted on the frame of the machine by a fixed arm 94 which fits into a groove 95 in the hub of the hand wheel, and holds the hub against the frame.

Referring to Figs. 1 and 2, the plate 17 for supporting the article 16 whose margin is to be coated may be adjusted up and down to vary the width of the marginal coating 15. Such adjustment is effected by a hand wheel 96 secured to a shaft 97 mounted in the frame of the machine and having a pinion 98 keyed thereto and meshing with a rack 99 secured to a slide 100 which in turn is attached to the supporting plate 17. The slide 100 is mounted in dovetailed guideways 101 formed in the frame of the machine. The rod 97 is provided with a locking mechanism for locking the supporting plate in any position it may be adjusted. The locking mechanism comprises a manually operable nut 102 which is threaded upon the shaft 97 and is adapted to be turned up against an abutment 103 on the frame of the machine so as to lock the shaft 97 and the pinion 98 thereon against rotation by drawing the conical head 104 on the shaft 97 into a similarly shaped socket in the frame.

When the machine is in operation the parts are in the position shown in Fig. 1. To operate the machine the motor is started by the usual switch 105. The motor 31 drives the coating liquid transfer drum 12 and delivers the coating liquid to the trough 13 which directs the flow of the coating fluid upon the lower margin

of the shoe 16. The motor also drives the rotatable disc 21 which prevents the coating liquid from splashing upwardly on the shoe. The lip 22 on the edge of the disc produces a sharp even line around the top of the marginal coating as the shoe 16 is manually turned to present the lower margin 15 to the flow of liquid from the discharge end 14 of the trough. In coating the shoe 15, the bottom rests upon the relatively small projection 18 of the supporting plate 17, and is maintained substantially parallel with the supporting plate as it is turned around on the projection 18 in a counterclockwise direction. When the parallel position of the shoe is maintained, the distance the lip 22 contacts with the shoe above its bottom will be substantially constant, and the width of the marginal coating will be constant. As an aid to maintaining such parallelism, the lower elevated portion 19 is provided for the toe portion of the bottom of the shoe to rest upon. Due to the fact that the support 18 is relatively small, it is adapted to fit into the curvature of the shank of the bottom of the shoe and maintain the point of contact of the lip 22 a substantially constant distance above the bottom of the shoe in that locality.

It will be understood that where the machine is to be used for applying marginal coatings of adhesive to shoes having a flat bottom and no arch at the shank 24, a flat supporting plate 17 may be used, and the raised portions 18 and 19 may be eliminated.

When it is desired to discontinue the operation of the machine, the marking disc 21 may be moved into its upper position, and the bottle reservoir 68 may be moved into its lower position as shown in Fig. 3 to permit the coating liquid conveying trough 13, supply tank 11 and the attached canal 79, to be removed and cleaned as previously described. The supporting plate 17 with its supporting slide 100 may be removed by releasing the locking nut 102 and pulling the slide upwardly out of the guides 101. When such parts are removed the drum 12 is accessible for cleaning.

While the details of this invention have been described, it is understood that they may be changed or modified without departing from the spirit of the invention, and it is desired to protect the invention within the scope of the claims appended hereto.

Having thus described my invention, what I claim and desire to protect by Letters Patent is:

1. In a machine for applying liquid coating to the lower margin of an article, a trough inclined downwardly towards its discharge end for conveying the coating liquid and discharging it upon the margin to be coated, a support for the article adjacent to the discharge end of said trough, a rotatable disc above the discharge end of said trough for forming a smooth top edge on the marginal coating, a tank for coating liquid, a drum rotatable about a horizontal axis and having its lower periphery positioned to contact with liquid in said tank and its upper periphery adapted to discharge coating liquid therefrom into said trough, means for returning the excess coating liquid to said tank, and means for maintaining the liquid level in said tank at a substantially constant level.

2. In a machine for applying liquid coating to the lower margin of an article, a trough inclined downwardly towards its discharge end for conveying the coating liquid and discharging it upon

the margin to be coated, a drum having its lower periphery adapted to rotate in a bath of the coating liquid, said trough having the upper edge of its bottom resting upon the upper periphery of said drum and inclined upwardly against the direction of rotation of the surface of said drum contacting therewith, means for resiliently holding said upper edge against said drum, and means for operating said holding means to permit the removal of said trough.

3. In a machine for applying liquid coating to the lower margin of an article, a trough inclined downwardly towards its discharge end for conveying the coating fluid and discharging it upon the margin to be coated, a tank for the coating liquid, a drum having its lower periphery adapted to rotate in contact with the coating liquid and discharge the coating liquid from its upper periphery into said trough, a projection extending upwardly from the receiving end of said trough and fulcrumed intermediate its ends on a bar seated in an upwardly opening socket in said projection, a manually operable support for the upper end of said projection adapted to normally hold said socket on said bar and said receiving end on the periphery of said drum, and means for manually operating said support so that said trough can be lowered and removed.

4. In a machine for applying liquid coating to the lower margin of an article, a tank for holding the coating liquid, a drum rotatable about a horizontal axis and having its lower periphery adapted to rotate in contact with the coating liquid in said tank, a trough inclined downwardly towards its discharge end for conveying the coating fluid and discharging it upon the margin of the article, said trough having its upper end arranged to scoop the coating fluid from the

periphery of the drum into said trough, a rotatable disc above the discharge end of said trough for limiting the height of the marginal coating applied to the article, means for moving said disc upwardly away from said trough, means for removing said trough from said machine, and means for removing said tank so that said disc, trough, tank and drum are made accessible for cleaning.

5. In a machine for applying liquid coating to the lower margin of an article, a trough inclined downwardly towards its discharge end for conveying the coating liquid and discharging it upon the margin to be coated, a drum below said trough and adapted to rotate in contact with a coating liquid bath and transfer the liquid to said trough, a rotatable disc above said trough for forming a smooth top edge on the marginal coating, said disc being driven by a shaft extending downwardly from above said disc, and means for pivotally moving said disc upwardly away from said trough so that the trough may be removed and said drum be made accessible for cleaning.

10 6. In a machine for applying a coating of adhesive around the foxing margin of a shoe having an arched shank, a support for the bottom of the shoe comprising an inclined support having a rounded projection adapted to fit within the curvature of the arched shank and a flat surface spaced from said rounded projection and adapted to support the toe and ball portion of the bottom when the toe points downwardly from said small projection, and means for flowing adhesive material on the foxing margin at the upper edge of the small projection.

HERBERT R. POLLEYS.
